UNITED STATES PATENT OFFICE

RUSSELL A. WOOD, OF CAMBRIDGE, MASSACHUSETTS

PENHOLDER INK FONT

Application filed June 3, 1932. Serial No. 615,127.

This invention relates to ink fonts, or ink feeding attachments for the common form of pen holder which is usually employed for holding a steel pen, and is to be distinguished
 5 from the type of devices ordinarily known as "fountain" pens, which have a hollow holder, within which a supply of ink is contained.

While the ordinary fountain pen is suitable
 10 for use in many instances where a continuous ink supply to the pen is desired, pens of this type are not conducive to good penmanship, or to sightly, or artistic writing, so that for bookkeeping, and for many similar purposes
 15 where fine appearance is desired, the ordinary steel pen is usually employed, which must frequently be dipped in an inkwell to renew the supply.

While steel pens, adapted to be used in an
 20 ordinary pen holder, have been provided with various forms of ink retaining clips, or the like, these devices have never, so far as I am aware, gone into extensive general use, as they have been found to be objectionable, or
 25 unsatisfactory, for various reasons.

The objects of my invention are to provide an attachment of simple and inexpensive construction which may be readily applied to practically any ordinary steel pen and holder, and will provide an ink holding chamber of a capacity equal to, or greater than that of many fountain pens, which will feed or supply the ink to the pen point, or nibs at the rate required while writing, without providing an excessive quantity, so as to cause blotting, and with which the supply of ink may be readily controlled by the application of a slight pressure with the forefinger of the writer when the pen holder is held in writing position.

I accomplish these, and other objects of my invention by providing an ink container of resilient material, as soft rubber, when is adapted to be mounted on the top side of the pen holder in a position which will not prevent the fingers of the writer from being held in the correct writing position, said container being provided with a tubular extension adapted to conduct the ink through the pen aperture to its under side, so that ink will be

supplied to the nibs of the pen in sufficient quantity for writing, usually by capillary attraction, but, if necessary, by the application of a slight pressure on the resilient walls of the container the attachment, when in position, in no way affecting the flexibility of the pen when writing and the construction permitting the ink chamber to be readily filled by collapsing the walls thereof, so that the ink may be drawn therein by suction.

For a more complete disclosure of the invention reference is made to the following specification, in connection with the accompanying drawing, in which:

Fig. 1 is a side elevation of a preferred embodiment of my invention, showing the attachment in position on a pen and holder.

Figs. 2 and 3 are sectional views at lines 2—2 and 3—3 of Fig. 1, respectively.

Fig. 4 is a perspective view illustrating the manner of use.

Figs. 5 and 6 are longitudinal central sectional views of modified forms of the attachment.

Figs. 7 and 8 are detail perspective views of another modification of the invention and

Fig. 9 is a similar view of the form shown in Fig. 5.

In the drawing *a* indicates a common form of pen holder and *b* a common form of steel pen, which is inserted therein, and, in the present instance, is shown as provided with an elongated aperture *c* between the nibs.

According to my invention I provide an elongated ink holder or container *d*, which is formed of soft or resilient rubber and is made hollow to provide an ink holding chamber *e*, which extends from one end nearly to the opposite end, the width of said container being slightly greater than the diameter of the holder *a* and the length thereof ordinarily being somewhat less than half the length of the ordinary holder, and being varied according to the ink capacity desired. Said container is adapted to be mounted on what may be considered as the top side of the pen holder, or the side corresponding to the top side of the pen which is inserted therein, the under side of said container being grooved longitudinally to receive the holder.

The end portion of the container opposite the end to which the chamber *e* opens is provided at each side with a resilient finger or flange *f*, said fingers being curved towards each other according to the curvature of the surface of the pen holder, so that they may grasp the latter and hold the container in any position longitudinally thereof in which it may be necessary to adjust the same.

In the form of the invention shown in Figs. 1 and 3, I provide a metal tube *g*, which is inserted in the open end of the container *d*, making a liquid tight connection therewith, said tube being curved reversely and tapered in diameter as it extends from the container, so that the under side of its end portion may touch the top side of the pen *b* and the tube may terminate and open directly over the aperture *c*. A flat projection *h* is also extended from the under side of the tube *g* in position to pass through the pen aperture, the front edge of said projection being flush with the open end of the tube *g*, and said projection having a notch *h'* in its opposite edge.

With the above described arrangement, the chamber *e* may be filled by collapsing the walls thereof and dipping the end of tube *g* in the ink and then permitting the walls to resume their normal shape. Then the container will be placed on the pen-holder and adjusted longitudinally to a position in which the projection *h* will extend thru the pen aperture *c*, and then it will be moved slightly from the pen until the edge portion of the pen at the end of its aperture engages the projection *h* in its notch *h'*, as shown in Fig. 1.

As thus arranged, a slight pressure on the walls of the chamber *e* will cause a drop of ink to be expelled from the tube *g* which will flow down on the surface of projection *h* by capillary attraction thru the pen aperture to the under side of the pen, so that ink will be supplied to the nibs, at the under side thereof in sufficient quantity for writing purposes.

In practice the holder will be held in the usual manner, as indicated in Fig. 3, and, while, ordinarily, ink will flow by capillary attraction to the under side of the pen in sufficient quantities for writing purposes, in case the supply should fail, or not be sufficient, a slight pressure on the walls or chamber will increase the supply to the extent desired until all the ink in the chamber and tube has been used. Under all conditions of use the container will be securely held in position on the holder by the fingers *f* and projection *h*.

The form of the projection which extends thru the pen aperture may be varied according to the different apertures which are formed in different pens.

For example, as shown in Figs. 5 and 9, if the pen aperture is nearly circular, the tube *g* will be provided with a correspondingly shaped projection, as *i*, which will pass loosely therethru. The construction otherwise being the same as already described.

In the form of projection *h*, shown in Fig. 1, the notch *h'* therein, which receives the edge portion of the pen, provides a shoulder which engages the underside of the pen and prevents the tube *g* from swinging upward away from the pen, practically locking the tube in this position. To accomplish this same result, the projection *i* is extended obliquely from the tube, so that its side opposite that which is flush with the end of the tube may be engaged with the under side of the pen in a similar manner.

In Figs. 7 and 8 a form of projection is illustrated which will act as a more positive lock in connecting the tube to the pen. In this instance the projection is in the form of a T-head *j*, which is arranged at right angles to the tube, the head of the projection being adapted to be passed thru the pen aperture when the tube is held at right angles to the pen, then, after the T-head has been thus inserted, the whole attachment will be swung into position on the holder, in which position the projection *j* cannot be withdrawn from the pen aperture. The whole attachment will thus be securely locked in position.

In lieu of the metal tube above described, the container may be provided with a tubular extension *h*, which will be formed integrally therewith, but which in the curing process may be hardened, particularly at its end portion, which will include the projection *h*, or its equivalent, as indicated in Fig. 6. This construction is considered to be preferable to that of Fig. 5, as it may be manufactured at less expense.

While ordinarily the attachment above described will only be used for desk purposes, when the attachment is to be carried in the pocket, the end of the tube may be screw threaded and a screw plug, as *m*, may be provided for closing the end thereof, as shown in Fig. 5, which will be removed when the attachment is to be placed in position.

Obviously other means than the resilient fingers *f* may be employed for holding the attachment in position, as a simple rubber band, but the arrangement shown is preferable.

The above described attachment has all of the important advantages of a fountain pen, if it is to be employed for desk purposes only, and is not to be carried in the pocket, and at the same time enables the use of a fine pointed steel pen for the particular purposes for which such pens are ordinarily used.

I claim:

1. An ink font for a pen holder in which a pen having a pair of nibs and an aperture

- therebetween is mounted, comprising an elongated container adapted to be secured on the top side of the holder with one end adjacent the pen-receiving end thereof, said container having a longitudinally extending ink-receiving chamber therein, the walls thereof being resilient and collapsible and having a tubular extension opening to one end of said chamber and arranged to extend over the top side of the pen to the aperture thereof and to terminate in open communication therewith, and means on said extension for engaging the pen in its aperture. 5 70
2. An ink font for a pen holder in which a pen having a pair of nibs and an aperture therebetween is mounted, comprising an elongated container adapted to be removably secured on the top side of the holder with one end adjacent the pen-receiving end thereof, 15 75
- 20 said container having an ink holding chamber therein extending longitudinally thereof, the walls thereof being resilient and collapsible, and having a tubular extension opening to said chamber and arranged to extend over the top side of the pen and to open over the aperture therein, and a projection on said extension adjacent its end arranged to extend through the pen aperture to conduct the ink to the under side of the pen. 25 80
3. An ink font for a pen holder in which a pen having a pair of nibs and an aperture therebetween is mounted, comprising an elongated hollow container of resilient material adapted to be secured on the top side 30 85
- 35 of the holder and providing an ink chamber having collapsible walls, and a tube opening at one end to said chamber and arranged to extend over the top side of the pen and to discharge the ink above the aperture there- 40 90
- 45 in, said tube having a projection at its discharge end arranged to engage the pen in said aperture and conduct the ink delivered by said tube through the aperture to the under side of the pen by surface conduction. 10 100
4. An ink font for a pen holder in which a pen having a pair of nibs and an aperture therebetween is mounted, comprising an elongated container adapted to be secured on the top side of the holder with one end adjacent the pen-receiving end thereof, said container having a longitudinally extending ink-receiving chamber therein, the walls thereof being resilient and collapsible, and having a tubular extension opening to one end of said chamber and arranged to extend over the top side of the pen, and to deliver the ink from said chamber directly above the pen aperture and means projecting from said extension at one side of the delivery opening arranged to extend through the pen aperture and to conduct the ink to the under side of the pen. 55 110
5. An ink font for a pen holder in which a pen having a pair of nibs and an aperture therebetween is mounted, comprising an elongated container adapted to be mounted on the top side of the holder and having means for removably connecting the same thereto, said container having an ink-receiving chamber extending longitudinally from one end, the walls thereof 60 115
- 65 top side of the holder and having means for removably connecting the same thereto, said container having an ink-receiving chamber extending longitudinally from one end, the walls thereof 70 120
- 75
- 80
- 85
- 90
- 95
- 100
- 105
- 110
- 115
- 120
- 125
- 130

being resilient and collapsible and having a delivery tube opening to said chamber at said end and arranged to extend over the top side of the pen and to provide a delivery orifice 5 above the aperture of the pen, and a projection extending from the under side of said tube in proximity to said orifice, said projection being constructed to extend through the pen aperture and having a T-shaped head for 10 engagement with the under side of the pen, to lock the tube thereto.

9. An ink font for a pen holder in which a pen having an aperture therethrough is mounted, comprising an elongated container 15 adapted to be mounted on the top side of the holder and having means for removably connecting the same thereto, said container having an ink-receiving chamber extending longitudinally from one end, the walls thereof 20 being resilient and collapsible and having a delivery tube opening to said chamber at said end and arranged to extend over the top side of the pen and to provide a delivery orifice above the aperture of the pen, and a projection 25 extending from the under side of said tube in proximity to said orifice, said projection being constructed to be passed through the pen aperture and having a transversely disposed T-head at its end for locking 30 the tube thereto when the container is in position on the holder.

10. An ink font for a pen holder in which a pen having an aperture therethrough is mounted, comprising an elongated container 35 adapted to be mounted on the top side of the holder and having resilient fingers for engaging opposite sides of the holder to hold the container thereon in different positions of longitudinal adjustment, said container 40 having an ink-receiving chamber extending longitudinally from one end, the walls thereof being resilient and collapsible and having a delivery tube opening to said chamber at said end and arranged to extend over the top 45 side of the pen and to provide a delivery orifice above the aperture of the pen, and a projection extending from the under side of said tube in proximity to said orifice and constructed to extend loosely through the pen 50 aperture.

11. An ink font for a pen holder in which a pen having an aperture therethrough is mounted, comprising an elongated container of resilient rubber adapted to be mounted 55 on the top side of the holder and having resilient means for engaging the holder to se-

cure the same in different positions of longitudinal adjustment thereon, said container having a longitudinally extending ink-receiving chamber therein provided with collapsible walls and having an integral tubular extension projecting from one end thereof in open communication with the adjacent end of said chamber, said extension being arranged to extend over the top of the pen and to provide a delivery orifice above the aperture 70 therein and having a projection on its under side adjacent said orifice arranged to extend loosely through the pen aperture, said projection and the adjacent end portion of said extension being hardened to non-resiliency. 75

12. In combination with a pen holder having a pen mounted in one end thereof, the pen having an aperture between its nibs, an elongated ink container of resilient material mounted on the top side of said holder and having resilient engaging means permitting longitudinal adjustment of the container thereon, said container having a longitudinally extending ink-receiving chamber therein and a tube extended from one end thereof 85 over the top side of the pen, said tube opening to the adjacent end of said chamber and having a delivery orifice over the pen aperture, and a projection on the under side of said tube extending through said aperture 90 and arranged for surface conduction of the ink discharged from said orifice to the under side of the pen.

13. In combination with a pen holder having a pen mounted in one end thereof, the pen having an aperture between its nibs, an elongated ink-container mounted in longitudinal relation on the top side of said holder and secured thereto, said container having an ink-receiving chamber extending longitudinally therein from the end thereof next the pen and terminating adjacent the opposite end, the walls of said chamber being resilient and collapsible and said container having a tubular extension opening to the end of said chamber next the pen and extending over the top side of the pen and opening to the aperture thereof, said extension having a transverse projection at its end engaged with the pen in the aperture thereof and arranged to conduct the ink delivered by said extension on its surface through the aperture to the under side of the pen. 110

In testimony whereof, I have signed my name to this specification.

RUSSELL A. WOOD.
